UNITED STATES PATENT OFFICE

STEPHEN W. BORDEN, OF SUMMIT, NEW JERSEY

EARTH ELECTRODE

Application filed June 16, 1928. Serial No. 286,045.

This invention relates to improvements in earth electrodes, and more particularly to those types consisting of driven pipes, or hollow receptacles buried in the earth and connected to the surface thereof by means of hollow pipes.

The objects of the improvements are to provide first, convenient and effective means for chemically treating the earth surrounding the electrode, and second, to provide facilities whereby the chemicals, particularly when used in the form of crystals, may be properly dissolved, and applied to the electrode automatically when water is applied to that portion of the electrode assembly which is flush with the ground and especially when the water consists of rain falling on the earth immediately surrounding the electrode.

The use of a drive point having exit holes for the solution and the use of a cable attaching device, having an opening therein connecting with the interior of the electrode, are not elements of the present invention although shown in the drawings, such elements being covered by my application Serial Number 106,397, for electrical ground anodes, filed May 3, 1926, Patent No. 1,737,562, dated Dec. 3, 1929.

The invention comprises the devices and combinations of devices described and claimed hereinafter in connection with the drawings and the equivalents thereof.

Fig. 1 is a plan view of a complete assembled electrode.

Fig. 2 is a front elevation partly in cross section.

Fig. 3 is a vertical cross section of a coupling including a water retaining ring.

Fig. 4 is a vertical cross section of a coupling without the retaining ring.

Fig. 5 is a cross-section on line 5—5 of Fig. 4.

In the drawings like parts are indicated by like symbols.

The electrode is so positioned in the earth that rain falling on the surrounding ground will flow by gravity to the cover of the electrode, where it passes through the holes H, Fig. 1, into the receiving chamber RC; when

the chamber is filled to the level of the discharge outlet DO, the water, which has now become a chemical solution due to the presence of chemical crystals in the receptacle, overflows into the discharge outlet and thence flows through the pipe P into the body of the electrode. When the water ceases to flow through the openings H, the receiving chamber RC does not become empty but remains full of water up to the level of the top of the discharge outlet, so that there is ample opportunity for slowly dissolving chemicals to form saturated solutions between rains or other applications of water to the electrode.

After the solution has been delivered to the inside of the electrode means must be provided for its exit to the surrounding earth. When the earth portion of the electrode consists of pipes joined by means of couplings, the couplings may be constructed as shown in Figs. 3 and 4. Referring to Fig. 3, the shoulder S serves two purposes. First, it provides a solid seat for the pipes, in order that the strain of driving may not come upon the pipe threads, and second, it provides a spacer between the two pipes in which depressions are formed as shown at D, Fig. 5, which depressions lead into exit holes, as EH, and which will not be closed when the pipe is screwed into place.

As the solution travels down the interior surface of the pipe it falls upon the shoulder S, and flows into the depressions D thence passes out through the exit holes EH into the surrounding earth. When the amount of solution is limited it is preferable that as much as possible of the solution be passed through the openings in the highest coupling, since the solution has a tendency to descend on the outside of the electrode, and in order to insure this, I sometimes add a water retaining ring as R in Fig. 3, which insures that the solution flowing down the inside surface of the pipe will pass out through the holes in the highest coupling. When the solution is supplied at a rate in excess of the flow capacity of the exit holes in the first coupling, the channel between the ring and the pipe fills up thus causing the solution to overflow

the ring and pass downward into the lower sections of the electrode. Since the entire electrode is generally filled with chemical crystals the solution, after passing through the ring in the uppermost coupling, has a tendency to find its way to the inner surface of the next section of pipe before it reaches the next lower coupling where the same action takes place as at the upper coupling.

10 Electrodes of the driven pipe type, and of the larger sizes, such as 2" diameter, are frequently driven to depths of 50 and 60 feet. With such depths and with the electrode completely filled with liquid there is a considerable hydrostatic pressure at the lower portions of the electrode with the result that the solution, as well as small chemical crystals, are forced out into the earth, even when the earth is of a relatively compact nature, and 15 20 a saturation of the surrounding soil is obtained in this manner which it is practically impossible to obtain by applying the solution to the soil at or near the surface of the ground and outside the pipe. Furthermore, the 25 maximum density of impregnation will exist immediately adjacent the pipe, which is the location where it will operate most effectively in reducing the resistance of the electrode since the resistance varies inversely as the 30 square of the distance from the electrode.

When only a relatively shallow strata of earth is available for the installation of earth electrodes, it becomes desirable to use electrode bodies of relatively large area such 35 40 bodies taking the form of small tanks or receptacles in the ground, these usually having a pipe connection to the surface of the ground. Electrodes of this type are frequently filled with chemicals and perforations are provided 45 to permit the solution to pass out into the surrounding earth. My receptacle, co-operating with holes in the cover of the enclosing chamber, may be used to advantage in connection with this type of electrode. No coupling is involved in such a combination.

I claim:

1. In a pipe coupling for earth electrodes; the improvement consisting of a centrally located internal shoulder, of sufficient width to form a seat for the pipe, said seat having a depression in its surface and openings through the coupling wall connecting the depression with the outside of the coupling.
2. In an earth electrode containing two or more sections of pipe joined by couplings; the improvement consisting of a coupling positioned between the ends of the joined sections, said coupling having an internal shoulder of sufficient width to form seats for the pipes said seats having depressions in their surfaces and openings through the coupling wall connecting the depressions with the outside of the coupling.
3. In an earth electrode containing two or more sections of pipe, joined by couplings;

the improvement consisting of a coupling positioned between the ends of the joined sections, said coupling having an internal shoulder, of sufficient width to form seats for the pipes said seats having depressions in their surfaces and openings through the coupling wall connecting the depressions with the outside of the coupling, and a receptacle surrounding the upper end of the electrode and having a discharge outlet overflowing into the interior of the electrode.

4. In an earth electrode containing two or more sections of pipe, joined by a coupling or couplings the improvement consisting of a coupling positioned between the ends of the joined sections, said coupling having an internal shoulder of sufficient width to form seats for the pipes said seats having depressions in their surfaces and openings through the coupling wall connecting the depressions with the outside of the coupling, and a receptacle surrounding the upper end of the electrode and having a discharge outlet overflowing into the interior of the electrode; and a covered enclosing chamber surrounding the receptacle, positioned above and in line with the receptacle and co-operating therewith.

5. In a hollow earth electrode, the improvement consisting of a receptacle surrounding the upper end of the electrode the receptacle having a discharge outlet overflowing into the interior of the electrode and a covered enclosing chamber surrounding the receptacle the chamber cover having openings therein positioned above and in line with the receptacle and co-operating therewith.

In testimony whereof I have signed my name to this specification.

STEPHEN W. BORDEN.
